CLAIM

The ornamental design for a cake stand, as shown and described.

DESCRIPTION

FIG. 1 is a top perspective view of a cake stand showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion of the cake stand shown within the area designated as 9 in FIG. 2; and,

FIG. 10 is an exploded perspective view of the cake stand. The dot-dash broken lines encircling portions of the cake stand in FIG. 2 and illustrated in the enlarged view in FIG. 9 form no part of the claimed design.

1 Claim, 10 Drawing Sheets
